(57) **CLAIM**

The ornamental design for a syringe, as shown and described.

DESCRIPTION

FIG. 1 is a top perspective view of a portion of a syringe showing our new design;

FIG. 2 is a front elevation view thereof;

FIG. 3 is a rear elevation view thereof;

FIG. 4 is a right elevation side view thereof;

FIG. 5 is a left side elevation view thereof;

FIG. 6 is a top plan view thereof;

FIG. 7 is a bottom plan view thereof;

FIG. 8 is a bottom perspective view thereof;

FIG. 9 is a top perspective view of another portion of the syringe showing our new design;

FIG. 10 is a right side elevation view thereof;

FIG. 11 is a left side elevation view thereof;

FIG. 12 is a front elevation view thereof;

FIG. 13 is a rear elevation view thereof;

FIG. 14 is a top plan view thereof;

FIG. 15 is a bottom plan view thereof;

FIG. 16 is a bottom perspective view thereof; and,

FIG. 17 is a front elevation view of the portions of FIGS. 1-16 combined to form the entire syringe showing our new design in an environment in which it may be used.

The broken lines in the Figures show portions of the syringe that form no part of the claimed design, and in FIG. 17 also show an unclaimed environment in which the syringe may be used.
